SUPPORT FOR HEATING APPLIANCES OR
OTHER WORKING TOOLS

Theodore Petersen, South Orange, N. J.

Application July 2, 1949, Serial No. 102,917

6 Claims. (Cl. 38—107)

1

The invention relates to a holder or support for a working tool or appliance, which is adapted for attachment to a work table, bench or the like, and particularly to such a holder of the folding type.

It is specifically applicable to, although not limited to, a holder for attachment to an ironing table, to support an electric flatiron during intervals in which the latter is supplied with electric current so as to be in the heated condition preparatory to use but is not actually in use for the desired ironing purpose, in order to effectively increase the working space on the table during such intervals while preventing scorching of the cloth or other table covering and fires which might occur if the flatiron in the heated condition is left standing on the table proper for too long a time, this holder being adapted to be folded back out of the way against the table when the latter is not in use.

Objects of the invention are to improve such a holder from the standpoint of simplicity in construction; ruggedness combined with light weight and an attractive appearance; efficiency and ease in operation; and low cost of manufacture.

The holder in accordance with one embodiment of the invention comprises a basket-like metal rack or container of special construction for supporting the electric flatiron or other heating appliance during periods of non-use for the ironing or other heating purpose. This rack is attached to the underside of the ironing board of the table at one end thereof by means of a mechanical linkage having a plurality of pivotal points, at least one of which is fixed and another substantially free with respect to the ironing board; for example, a pair of double-articulated hinges, these hinges being operable to swing the basket or rack to an optimum "working" position in which it extends outwardly from the end of the board, and, alternatively to an idle or "rest" position in which it is folded back on top of the board. The hinges for this purpose include inherent motion limiting means adapted for holding the basket or rack in its working position when it is swung in one direction, frictional retaining means for providing the necessary "brake" on their motion, and a lost-motion component to enable the required range of angular motion to be obtained.

A feature of the invention is the use for the base of the basket or rack supporting the electric flatiron, of a plurality of spaced, flat metal bars disposed so that in the working position of the

2

holder they slope gradually away from the upper surface of the ironing board and provide means for enabling the flatiron to be slid from the ironing surface of the board to the rack, and from the rack back to the ironing surface of the board, without the necessity of lifting the flatiron, thereby lessening fatigue to the user in the ironing operation.

Another feature is an auxiliary pad of sound-deadening and heat-insulating material adapted for ready attachment to the metal basket or rack of the holder of the invention to suppress operation noises and prevent injury to the working surfaces of the flatiron and basket during operation; and adapted for ready detachment therefrom when the conditions of use of the equipment does not require it.

Another feature is the provision in the construction of the rack at little additional cost of a simple guide for the electric current supply cord attached to the flatiron during operation of the latter for its ironing purpose and the process of sliding the flatiron back and forth between the ironing surface and the rack, in order to prevent "fouling" of the cord, undue bending wear thereon, and possible injury to the associated electric plugs caused by these operations.

These and other objects and features of the invention are fully explained in the following description thereof to be read in conjunction with the accompanying drawings in which:

Figs. 1 and 2 respectively show a side elevation and a top plan view of one embodiment of the folding holder of the invention applied to an ironing board;

Fig. 3 shows an end elevation view of the folding holder of the invention taken along the line 3—3 of Fig. 2, partly in section to show structural details;

Fig. 4 shows a side view of a portion of one of the hinges used in the folding holder of the invention, partly in section to indicate more clearly other details of construction;

Figs. 5 and 6 show different views of one type of friction washer which may be used in each of the hinges of the folding holder of the invention, to illustrate its construction; and,

Fig. 7 shows a sectional view of a fragment of the detachable heat-insulating and sound-deadening pad of the invention, illustrating one type of construction which may be used.

The holder or support in accordance with one practical embodiment of the invention is shown in Figs. 1 to 3, drawn to a scale of $\frac{3}{4}$ inch equals 1 inch, as applied to an ironing board having

3

a cloth or other covering 1a, shown in fragmentary form, of an ironing table. This holder includes a metal basket or rack 2 of special construction and a pair of offset, double-articulated hinges 3 and 4 connecting the basket to the bottom of the board at one end thereof. The hinges 3 and 4 are adapted for operation in unison to swing the basket to an optimum position, to be defined later, with respect to the horizontal ironing surface of the board, for supporting an electric flatiron between intermittent ironing operations, so as to leave the entire working surface of the board free for other purposes during these intervals, such as the brushing or folding of the textile materials being ironed; and alternatively 15 to swing the basket to a rest position in which it is folded back against the top of the board.

The basket 2 includes a frame portion of substantially rectangular shape. This frame portion includes a cold rolled steel strip of elongated, rectangular cross-section ($\frac{1}{2}'' \times \frac{1}{8}''$) and suitable length bent at two points around a radius perpendicular to the longest transverse dimension ($\frac{1}{2}''$) so as to provide an intermediate straight portion forming one long side 5 and two straight end portions of equal length at right angles thereto forming the two parallel short sides 6 and 7 of the frame, the two bends being suitably rounded to improve the appearance of the basket and to obviate undesirable sharp edges. The other long side 8 of the frame, parallel to the long side 5, comprises a cold rolled steel rod of circular cross-section ($\frac{1}{16}''$ diameter) extending between and affixed at its ends to the two short sides 6 and 7 of the frame at corresponding points near their free ends. Silver brazing is preferably used for joining the rods to the frame in order to provide strong, clean joints.

Three cold rolled steel bars 9, 10 and 11 of the same elongated, rectangular cross-section ($\frac{1}{2}'' \times \frac{1}{8}''$) as the steel strip forming three sides of the frame are used for the base of the basket. They extend in parallel with each other between the round rod forming the long side 8 and the portion of the steel strip forming the other long side 5 of the frame, at respectively equally spaced points between the two short sides 6 and 7 thereof. Each of the three cross-bars 9, 10 and 11 has a corresponding bend in it such that the longer portion of the bar slopes downwardly gradually; for example, at an angle of approximately 12 degrees, as shown, away from the round rod 8, and the remaining short portion with the holder in its working position rises approximately vertically from the bend to the lower edge (having the $\frac{1}{8}''$ transverse dimension) of the flat steel strip portion forming the long side 5 of the frame. The cross-bars 9, 10 and 11 are joined securely at their ends to the long sides 5 and 8 of the frame, preferably by silver brazing. The upper surfaces of the inclined portions of the three cross-bars provide supporting surfaces for the electric flatiron, indicated in Figs. 1 and 2 by the dot-dash phantom outline 12, and enable it to be slid, without lifting, from the horizontal surface of the ironing board 1 into the basket 2 during intervals between ironing operations and back onto the working surface of the ironing board when the ironing is to be continued. The vertically rising portions of the cross-bars 9, 10 and 11 cooperate with the portion of steel strip forming the long side 5 and the portions of steel strip forming the short sides 6 and 7 of the frame to prevent the flatiron from falling out of the basket 2.

4

A short piece of cold rolled steel rod 13 of circular cross-section ($\frac{1}{8}''$ diameter) extends across one corner of the frame of basket 2 between the portion of steel strip forming the short side 6 and the adjacent portion of the metal rod forming the long side 8 of the frame, to form a small enclosed opening between the frame and rod. This opening may be used as a guide for the cord, indicated by the phantom outline 14 in Fig. 1, supplying electric current from a power outlet to the flatiron 12, during the intervals in which the latter is moved back and forth on the working surface of the board 1 for its ironing purpose and during the intermediate intervals in which it is shifted back and forth between the working surface of the board and the basket 2. The rod 13 may be attached at its ends to the frame by silver brazing. As indicated in Fig. 2, the rod 13 may be bent at an intermediate point to provide a more suitable shape for the guide opening in order to prevent binding of the cord in triangular corners.

Each of the hinges 3 and 4 includes an individual small bracket 15 and 15', respectively, in the form of a T, which may be made from a single piece of 16 gauge ($\frac{1}{16}''$ thickness) mild steel plate of suitable length and width, by bending the centrally located portion sharply downward so as to form a loop and compressing the sides of the loop together to form the stem 16 of the T at right angles to the two collinear flange portions 17 forming the cross-bar of the T. Two or more holes are provided in the flange portions 17 for screws to attach the two brackets 15 and 15' to the bottom of the ironing board 1 at spaced points separated by a distance determined by the width of the end of the average ironing board. The brackets 15 and 15' are respectively spaced inwardly from the sides of the ironing board by the same distance and inwardly from the end of the ironing board by the same distance.

Each hinge 3 and 4 also includes a metal member 18 comprising a channel section having two parallel, longitudinally extending flanges 19 and 20 connected by a web 21, bent in the form of a V with the open side of the channel on the inside, the two straight arms 22 and 23 of the V-shaped member being preferably disposed, as shown, so as to provide an angle of approximately 50 degrees between them, and the bottom of the V being suitably rounded, as shown, to avoid a sharp edge. Each hinge member 18 may be formed integrally from a single piece of 16 gauge mild steel plate of suitable dimensions by means of a number of bending operations using a special commercial bending machine. The width of the opening between the parallel flange portions 19 and 20 of the channel section of each hinge member 18 is selected to accommodate the width of the stem 16 of each bracket 15 and 15' and the width of the steel strip forming the short sides of the basket frame, to be pivotally mounted therein when the hinge is assembled in the manner to be described later.

Motion limiting means inherent in each of the hinges 3 and 4 is provided by suitable shaping of the upper end of the arm 22 of the V-shaped member 18 of each hinge 3 and 4, extending beyond the pivoting point, and the provision of a lug 24 the upper surface of which forms a shoulder at a suitable location on the outside of the other arm 23 of that member. As shown in the side view of the hinge member 18 in Fig 4, in which the upper portion of one flange portion 19 of arm 23 is shown broken away, the lug 24

75

may be made integral with the member 18 by the provision of vertical cuts in the top of the arm 23 such as to allow the top portion of the web 21 to be folded back to form a loop the upper surface of which provides the desired shoulder at the proper location.

The free end of the steel strip forming the short side 6 of the frame of basket 2, projecting beyond the point of connection of one end of the round rod 8 thereto is pivotally mounted between the flanges 19 and 20 at the top of arm 23 of member 18 of hinge 3 by means of a tubular rivet 25 extending through corresponding holes in these members and in a friction washer 26. Similarly, the free end of the steel strip forming the other short side 7 of the basket frame, projecting beyond the point of connection of the other end of the round rod 8 thereto is pivotally mounted between the flanges 19 and 20 at the top of the arm 23 of member 18 of hinge 4 by means of a second tubular rivet 27 extending through corresponding holes in these members and in a second friction washer 28. The stem 16 of the T-shaped bracket 15 is pivotally mounted between the parallel flanges 19 and 20 at the top of arm 22 of member 18 of hinge 3 by means of a third tubular rivet 29 extending through corresponding holes in these members and in a third friction washer 30. Similarly, the stem 16 of the T-shaped bracket 15' is pivotally mounted between the parallel flanges 19 and 20 at the top of arm 22 of member 18 of hinge 4 by means of a fourth tubular rivet 31 extending through corresponding holes in these members and in a fourth friction washer 32.

Each friction washer 26, 28, 30 and 32 may be of the known commercial type illustrated in the two views of Figs. 5 and 6. This type of friction washer, which is made from spring steel, is of saucer shape when uncompressed and has a number of radial slots in it forming outwardly extending resilient tabs or cusps which, when compressed by a tubular rivet or other securing means, collectively furnish a component of friction. The friction components provided by the friction washers in hinges 3 and 4 are utilized to slow-up the motion of the folding holder when the latter is operated to the working or to the rest position so as to prevent injury to any of its parts and undesired crashes when the basket 2 hits the board 1 or the motion limiting shoulder provided by the lug 24 on the member 18 of each hinge 3 and 4. These friction components also serve to maintain the basket 2 in its rest position folded back against the top of board 1 when the ironing table is folded up and stored away at the end of a period of use. In that case, the rounded V-shaped members 18 in hinges 3 and 4 may serve as feet to support the table on end thereby protecting the board 1 and its covering from dust and dirt.

As illustrated in Figs. 1 and 2, an auxiliary pad 33 made from heat-insulating and sound-deadening material may be applied as a cushion between the basket 2 and the electric flatiron 12 if it is desired to prevent injury to the finish of the supporting metal surfaces of the basket due to the application of heat thereto from the heated flatiron for a considerable time; to prevent scratching of the bottom surface of the flatiron by the metal surfaces of the basket when the flatiron is being shifted back and forth between the ironing surface of the board and the basket 2 between intermittent ironing operations; or to prevent annoying noises due to the flatiron hit-

ting the metal parts of the basket during such shifting. As shown, parts 33a at one end of the pad 33 may be made to fold over the round rod 8 and the opposite end 33b of the pad may be secured to the steel strip forming the long side 5 of the basket frame in a position such that its upper edge is co-planar with the upper edge of the latter to hold this pad in place, and the remaining portion of the pad is bent so as to conform with the inside of the basket 2 and to lie flat over the upper surfaces of the cross-bars 9, 10 and 11 forming the base of the basket. Therefore, this pad may be easily attached to the basket 2, and easily detached therefrom by the user of the equipment when the condition of use of the latter are such as not to require the pad. In one form of construction illustrated in Fig. 7, the pad may comprise an envelope 34 made from a thin sheet of Duralumin closed by the lap joint 35 and containing a filling 36 of asbestos fibre or other suitable material to provide the desired heat-insulating and sound-deadening properties to the combination, as well as the required stiffness.

25 In the operation of the holder of the invention, the hinges 3 and 4 allow the basket to be swung to the right by the user of the equipment to the working position shown by solid lines in Fig. 1 in which the basket extends outwardly from the end of the board 1 with the upper edges of the steel strip forming the short sides 6 and 7 of the basket frame substantially in the same plane as the working surface of the board 1 and with no part of the basket or hinge structure in a position higher than the top of the board 1. The basket 2 will be held in that working position because further movement of the members 18 of the hinges 3 and 4 is prevented by the shaped upper surfaces of the arms 22 of these members being brought into abutment with the lower surfaces of the flange portions 17 of the brackets 15 and 15', respectively, and further downward movement of basket 2 is prevented by the lower edges of the short sides 6 and 7 of the basket frame being brought into engagement with the shoulders formed by the properly located upper surfaces of the lugs 24 on the arms 23 of the members 18 of the two hinges 3 and 4, which lugs are held stationary due to the stopping of further movement of these hinge members.

55 When the ironing table is not in use, the hinges 3 and 4 allow the basket 2 to be swung by the user upwardly from the working position over an angle greater than 180 degrees until it is brought to rest folded back on top of the board 1, as indicated in Fig. 1 by the dot-dash phantom outline 37 showing the exact position of the basket and the hinges for that condition of adjustment. The angular movement of over 180 degrees from the working position to the rest position is enabled because of the lost motion component inherent in the two double-articulated hinges 3 and 4. This required angular range of movement could not be obtained by the use of hinges having a single pivotal point because some part of the hinge or basket would strike the board after the basket had traversed a much smaller angle because of insufficient clearance.

65 70 The use of single pivot hinges, making the angular movement less than 180 degrees between the working and rest positions of the basket, would require that this pivotal point be located higher than the horizontal surface of the board 1 in order to provide the desired clearances. This

would be undesirable because of the danger of the flatiron striking parts of the basket or hinges which would be located above the working surface of the board 1 in the working position of the holder, in the process of shifting the flatiron back and forth between that surface and the basket.

The entire basket 2 is, preferably, cadmium plated and the hinges 3 and 4 are, preferably, sprayed with colored enamel and oven-baked, so that the entire holder has an attractive appearance.

The particular embodiment of the holder of the invention illustrated and described has the following pertinent dimensions. The distance between the center lines of the brackets 15 and 15' when attached to an ironing board is approximately $10\frac{1}{4}$ inches, so that the holder will be applicable to ironing boards having widths at their wider ends of as low as 12 inches. The width of the rectangular frame of the basket 2 between the short sides 6 and 7 thereof is approximately 10 inches, and the length between the long sides 5 and 8 of the frame is approximately 5 inches. The depth of the basket (inside dimension) at its deepest point is approximately 1.25 inches. The spacing between the near end of the board 1 and the round rod forming the long side 8 of the basket frame is approximately 1.5 inches.

The weight of the entire holder including the metal basket and hinge structures illustrated and described is less than one pound, and may be made of even less weight if lighter materials are used in its construction.

Although the invention has been described as applied to a holder for an electric flatiron for attachment to an ironing table, it is apparent that it is applicable as well to holders for other types of heating or other tools; for example, an electrically-operated soldering iron or electrical welding equipment, for attachment to any suitable working bench or table. It is understood that the particular materials and the dimensions specified for the several parts of the holder of the invention are given by way of example only, and that other suitable materials and dimensions may be used. Various other modifications of the holder or support illustrated and described which are within the spirit and scope of the invention will occur to persons skilled in the art.

What is claimed is:

1. In combination with a work table having a horizontal top working surface, a working tool holder, a multi-articulated hinge structure connecting said holder to the bottom of said table near one end thereof, said hinge structure having at least one pivot point fixed with respect to said table and at least one other pivot point substantially free with respect thereto and being adapted to swing said holder in one direction to an optimum working position extending outwardly from said one end of said table for transferring a working tool between said horizontal working surface of said table and said holder, and alternatively to swing said holder in the opposite direction to another position over 180 degrees from said working position in which it rests on top of said table, this range of angular motion of said holder being obtainable because of the lost motion component inherent in said multi-articulated hinge structure, the portions of said hinge structure extending between the fixed and free pivot points thereof being shaped so as to provide the required clearance to prevent

interference between said table and said hinge structure when said holder is swung between said working position and said other position and motion limiting means inherent in said hinge structure cooperating with said table and said holder to maintain the latter in said working position when it is swung thereto in said one direction.

2. In combination with an ironing board having an upper working surface and an electric flatiron for use thereon adapted for connection by a current supply cord to an electric power source, a basket-like holder for supporting said flatiron off said board between intermittent ironing operations on said working surface, hinging means connecting said holder to the bottom of said board near one end thereof and adapted to swing said holder alternatively to an optimum working position extending outwardly from said one end of said board for easily transferring said flatiron between said board working surface and said holder, said holder including a metal frame of substantially rectangular shape having three sides formed by flat metal strip disposed so that its long transverse dimensions are vertical when said holder is in said optimum working position, and a fourth side formed by a straight metal rod of circular cross-section extending between and affixed at its ends to the metal strip portions forming two parallel sides of said frame, and another base portion comprising a plurality of parallel flat metal strips extending between and affixed to opposite sides of said frame at spaced points between the other two opposite sides thereof and a second metal rod extending across one corner of said frame portion between and affixed at its ends to the metal members forming the adjacent sides of said frame portion at said one corner thereof, to form a small enclosed space between said second metal rod and said frame portion, which may be used as a guide for said current supply cord when said cord is connected therethrough and through the interstices in the base portion of said holder between said power source and said flatiron during the periods in which the latter is in use for ironing operations on said working surface of said board and during intermediate periods in which it is being shifted back and forth between said working surface of said board and said holder.

3. In combination with an ironing table including an ironing board having a horizontal top working surface, and an electric flatiron, a basket-like holder for supporting said electric flatiron between intermittent ironing operations on said board, a pair of identical double-pivot, offset hinges connecting said holder to the bottom of said board near one end thereof, one pivot point of each of said hinges being fixed with respect to said board and the other pivot point being substantially free with respect thereto, said pair of hinges being adapted for operation in unison to swing said holder to an optimum position extending outwardly from said one end of said board for the shifting of said electric flatiron between said working surface of said board and said holder and such that no part of said holder or said hinges are located higher than said working surface of said board, and alternatively to swing said holder over an angle greater than 180 degrees from said working position to another position in which it is folded back on top of said board, the portion of each hinge located between the two pivot points thereof being bent longitudinally away from said board

to provide sufficient clearance space to prevent interference between said hinge portion and the end of said board when said holder is swung between said working and said other position and motion limiting means inherent in said hinges cooperating with said board and said holder to maintain said holder in said working position when it is swung thereto from said other position.

4. The combination of claim 3, in which each of said hinges includes a bracket and a V-shaped member having two straight arms disposed at a given angle with respect to each other, said member being pivotally connected at the free end of one arm to the associated bracket, the V-shaped members of said pair of hinges being respectively pivotally connected at the free ends of their respective other arms to opposite sides of said holder, the two brackets of said hinges being affixed to the bottom of said board near said one end thereof at respective points spaced from each other and respectively located at the same distance inwardly from opposite sides of said board and at the same distance inwardly from said one end thereof, the said given angle between the two straight arms of the V-shaped member of each hinge being selected to provide the necessary amount of clearance between the hinges and said board when said holder is swung to said working position or to said other position.

5. The combination of claim 3 in which said holder includes a frame of substantially rectangular shape and suitable dimensions, one long side and the two parallel short sides of which comprise straight portions of flat metal strip disposed so that the longest transverse dimensions thereof are vertical when said holder is in said working position, the other long side of said frame comprises a straight metal rod extending between and affixed at its ends to the metal strip portions forming the short sides of said frame at corresponding points a short distance from the free ends thereof, each of said hinges includes a T-shaped bracket having a stem and two collinear flange portions at right angles thereto respectively extending to opposite sides of the stem, and another hinge member of rounded V-shape including two straight arms disposed with a given interior angle between them, one arm of the V-shaped member of each hinge being pivotally connected at its free end to the stem of the associated bracket and the other arms of said members being respectively pivotally connected to the free ends of the metal strip portions forming the opposite sides of said holder frame, the flange portions of the brackets of the two hinges being affixed to the bottom of said board near said one end thereof at points spaced from each other by a distance determined by the length of the long sides of said frame and symmetrically located with respect to the opposite sides and the end of said board, said motion limiting means inherent in said hinges being provided by proper shaping of the upper surfaces of the free ends of said one arm of the V-shaped members of said hinges and a lug forming a shoulder on the outside of said other arm of the V-shaped member of each hinge so that when said holder is swung to said working position by said hinge the shaped surface of said one arm of each V-shaped hinge member engages in abutment with the bottoms of the flange portions of the associated bracket and the shoulder

formed by the lug on said other arm of each of said V-shaped members engages in abutment with the lower edge of one of the metal strip portions forming the two opposite short sides of said frame.

- 5 6. The combination of claim 1, in which said holder includes a substantially rectangular frame the two parallel short sides of which extend in a direction perpendicular to said one end of said 10 table and are formed from flat metal strips disposed with its long transverse dimensions vertical when said holder is in said working position, and said hinge structure comprises a pair of offset, double-articulated hinges each comprising a 15 T-shaped metal bracket having a stem and two collinear flange portions at right angles thereto respectively located on opposite sides of the stem, a hinge member comprising a metal channel section having two longitudinally extending 20 flanges connected by a web, bent into a V-shaped form with the open side of the channel section on the inside to provide two straight channel arms disposed so as to provide a given interior angle between them, two tubular rivets and two 25 friction washers, the stem of the bracket of each said hinge being inserted between the parallel flanges at the free end of one arm of the associated V-shaped member and being pivotally connected thereto by means of one of the two 30 tubular rivets for that hinge extending through corresponding holes in said stem, said flanges and one of the two friction washers for that hinge, the ends of the two metal strip portions forming the opposite short sides of said holder 35 frame being respectively inserted between the parallel flanges at the free end of a different one of the other arms of the V-shaped members of the respective hinges and being pivotally connected thereto by the third and the fourth 40 tubular rivet, respectively, extending through corresponding holes in the connected arm and in the third and the fourth friction washer, respectively, said given interior angle between the two arms of each V-shaped member in said hinges 45 being selected to provide the required clearances between said table and said hinges when the holder is swung by the latter to said working position or to said other rest position, and the friction washers being utilized at the pivoting 50 points of said hinges to provide components of friction therein such as to slow up the motion of said holder sufficiently to prevent injury to any of the parts of said holder or of said hinges and undesired crashes when said holder comes 55 in contact with said motion limiting means inherent in said hinges or the top of said table.
